(57) **CLAIM**

The ornamental design of a chip carrier for biosensor apparatus, as shown and described.

DESCRIPTION

FIG. 1 is a top isometric view of a chip carrier for biosensor apparatus showing our new design, with the carrier shown projecting from the cover of a measuring cassette; FIG. 2 is a bottom isometric view thereof; FIG. 3 is a top isometric view thereof, with the carrier shown within the cover of a measuring cassette; FIG. 4 is a bottom isometric view thereof; FIG. 5 is a top isometric view thereof, shown carrying a chip; FIG. 6 is a bottom isometric view thereof; FIG. 7 is an end view thereof; FIG. 8 is a bottom plan view thereof; FIG. 9 is a side view thereof; FIG. 10 is a top plan view thereof; FIG. 11 is an end view thereof, opposite that shown in FIG. 7; FIG. 12 is a top isometric view thereof shown without the chip; FIG. 13 is a bottom isometric view thereof; FIG. 14 is an end view thereof; FIG. 15 is a bottom plan view thereof; FIG. 16 is a side view thereof; FIG. 17 is a top plan view thereof; and, FIG. 18 is an end view thereof, opposite that shown in FIG. 14. The broken line showing of the cover and chip are for illustrative purposes only and forms no part of the claimed design.
